DESIGN FOR A BUTTON OR SIMILAR ARTICLE

Daniel Kasen, Newark, N. J.

Application June 7, 1947, Serial No. 139,527

Term of patent 3½ years

(Cl. D17—2)

To all whom it may concern:

Be it known that I, Daniel Kasen, a citizen of the United States of America, residing in Newark, county of Essex, and State of New Jersey, have invented a new, original, and ornamental Design for a Button or Similar Article, of which the following is a specification, reference being had to the accompanying drawing, forming part thereof, wherein,

I claim:

The ornamental design for a button or similar article, substantially as shown.

DANIEL KASEN.
